UNITED STATES PATENT OFFICE.

THOMAS MEIKLE, OF LOUISVILLE, KENTUCKY.

PLOW.

SPECIFICATION forming part of Letters Patent No. 234,920, dated November 30, 1880.

Application filed October 4, 1880. (No model.)

To all whom it may concern:

Be it known that I, THOMAS MEIKLE, of Louisville, in the county of Jefferson and State of Kentucky, have invented certain new and useful Improvements in Plows; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improvement in plows; and it consists in so constructing the parts that an adjustable shin may be attached to the mold-board so as to be held firmly in place by a single bolt, and at the same time form part of the landside of the plow.

In the annexed drawings, making a part of this specification, Figure 1 is a side elevation. Fig. 2 is a perspective view, showing the plow with the shin detached. Fig. 3 is a vertical section. Fig. 4 is a sectional bottom view. Fig. 5 is a perspective view of the detachable shin-piece.

The same letters are employed in all the figures in the indication of identical parts.

A is the mold-board. B is the share. C is the standard. D is the detachable shin, and E is the landside.

The mold-board A is cut away along its front edge to receive the upper flange of the shin-piece D.

The landside E is cut away in front into the form shown in Figs. 1 and 2, the inner edge being beveled to form the recess shown in Fig. 2, which receives a projection or tongue

formed on the lower edge of the shin-piece, as shown at D' in Fig. 5. This projection fits closely between the beveled edges of the landside and mold-board, while the downwardly-projecting flange D² is received into the recess formed at E' between the rear end of the share and the front end of the landside, in which it is confined by the bolt D³ passing through the flange into the standard and frog.

The vertical exposed face of the piece D is flush with the landside, and the upper inclined face is flush with the curve of the mold-board. The piece being attached by a single bolt may be easily detached whenever the edge becomes worn.

I do not claim, broadly, a detachable shin-piece or cutter, my invention being confined to the mode of constructing and attaching it.

What I claim as my invention, and desire to secure by Letters Patent, is—

A plow combining in its construction the mold-board and landside, cut away to form a recess between their upper edges, and a shin-piece having a tongue or projection, which is received between the mold-board and landside, and a downwardly-extending flange, which lies in a recess formed between the landside and share, with which it is flush, and confined by a single bolt, substantially as set forth.

In testimony that I claim the foregoing I have hereunto set my hand this 28th day of September, 1880.

THOMAS MEIKLE.
